UNITED STATES PATENT OFFICE.

JOHN H. BROGAN, OF PHILADELPHIA, PENNSYLVANIA.

EXERCISING DEVICE.

1,012,802.

Specification of Letters Patent. Patented Dec. 26, 1911.

Application filed January 22, 1910. Serial No. 539,571.

To all whom it may concern:

Be it known that I, JOHN H. BROGAN, a citizen of the United States, residing at Philadelphia, in the county of Philadelphia and State of Pennsylvania, have invented 5 certain new and useful Improvements in Exercising Devices, of which the following is a specification.

This invention relates to exercising devices and more particularly to that class of exerciser adapted to be gripped by the two hands and maneuvered about the body.

The main object of my invention is to produce a device of the kind that when 15 properly used will bring as many of the muscles of the body as possible into active and strenuous play, even into violent operation, if desired.

With this object in view, I have produced 20 an exerciser in which elasticity has been eliminated as a feature, thus causing a positive action upon the muscles brought into play.

One of my principal objects is to produce 25 a strong, durable and efficient device, at a cost sufficiently low to be within the reach of almost any one.

With these and other objects in view, I endeavor to clearly illustrate my invention 30 in the accompanying drawings, in which—

Figure 1 is a top plan view of my exerciser, Fig. 2 is a view of the handle of my device with the hand grip in longitudinal section, Fig. 3 is a longitudinal section of 35 one end connecting strap, showing the reinforcing means and a portion of the handle, Fig. 4 is a detail of the reinforcing device, Fig. 5 is a view of the central part of the strap shown in section with a shortening 40 device, Fig. 6 is a device for shortening the strap.

Like numerals of reference indicate like parts throughout the several views and in the specification.

My exerciser consists of a flexible non-elastic member 1, approximately the length 45 of a person's arm. This member is attached at each end to an arc-shaped handle or bail as 2 and 3, to which are secured the revolving hand grips 4 and 5, through the medium of the bosses 6 which are counter sunk into the ends of the hand grips and

form bearings 7 for the ends of the bails 8, the extreme ends of which are enlarged to form a head 9. The bosses 6 are secured 55 to the hand grips by nails or screws 10, or by any other suitable means.

The ends 11 of the member 1 are passed over reinforcing members 12 which engage the bails 2 and 3 and return upon themselves forming an eye 13 therein which is somewhat larger than the bail allowing of its free movement on the bail. The member 1 and the reinforcing members 12 are secured to one another and to the bail 65 through the medium of the rivets 14 or the like. The portion 15 of the reinforcing member 12 which bears against the bail member is arc-shaped and has a smooth surface so that it will have a free and easy 70 movement on the bail and will readily slide from one part to another thereof.

A shortening device 16, may be secured to the member 1 for the purpose of changing the length of the exerciser as shown in 75 Fig. 4.

The member 1 may be constructed of any desired flexible, non-elastic material such as leather or the like. This member has a swinging motion on the bails and also has 80 a lateral sliding motion thereon. The hand grips have a revolving motion on the bails and these three independent motions permit of a rapid and easy movement of the parts making the exerciser adapt itself to 85 any angle or position.

The exerciser is preferably about the length of the arm of the person using it but may be longer or shorter as found desirable, the shorter the device the more violent the exercise. When lengthened it becomes milder.

To procure the best results the hands should embrace the hand grips with the palms facing outwardly and the exerciser 95 should be raised first above the head, then lowered toward the back of the body and maneuvered into as many positions as possible. When properly used this exerciser will bring practically all the muscles of the 100 arms and trunk of the body as well as many of the muscles of the lower extremities into play, expands the chest, enforces deep breathing and excites the blood into a rapid

coursing through the veins giving a most delightful tingling and refreshing sensation.

The members 1 may be rigid instead of flexible and various changes may be made from the form herein shown without departing from the spirit of my invention.

Having described my invention I claim and desire to secure by Letters Patent:—

- 10 1. An exercising device consisting of a non-elastic member approximately the length of the reach of a user's outstretched arms, and movable handles on the ends of said member.
- 15 2. An exercising device consisting of a non-elastic member approximately the length of the reach of a user's outstretched arms, and universally movable handles on the ends of said member.
- 20 3. An exercising device consisting of a non-elastic member approximately the length of the reach of a user's outstretched

arms, and universally movable handles on the ends of said member, said member being flexible.

25 4. An exercising device consisting of a non-elastic member approximately the length of the reach of a user's outstretched arms, and universally movable handles on the ends of said member, said member being flexible, and means for shortening said member.

30 5. An exercising device consisting of a non-flexible member approximately the length of the reach of the outstretched arms 35 of a user, means for shortening said member, handles slideable on said member and rotatable gripping members on said handles:

In testimony whereof I affix my signature, in presence of two witnesses.

JOHN H. BROGAN.
